UNITED STATES PATENT OFFICE.

EDGAR P. DORMAN, OF BALTIMORE, MARYLAND, ASSIGNOR TO THE CROWN CORK AND SEAL COMPANY OF BALTIMORE, OF BALTIMORE, MARYLAND, A CORPORATION OF MARYLAND.

PACKAGING MACHINE.

Application filed February 11, 1918. Serial No. 216,465.

To all whom it may concern:

Be it known that I, EDGAR P. DORMAN, a subject of Great Britain, residing at Baltimore, and State of Maryland, have invented 5 certain new and useful Improvements in Packaging Machines, fully described and represented in the following specification and the accompanying drawings, forming a part of the same.

10 This invention relates to improvements in packaging machines.

It is an object of the invention to provide a capping machine, capable of applying closures to bottles at a high rate of speed 15 and such that the percentage of loss due to breakage of bottles or imperfect capping will be substantially reduced notwithstanding the high speed of operation.

It is a further object of the invention to 20 provide a packaging machine utilizing a single capping mechanism which is capable of use in connection with any one of a plurality of types of fillers, such as are now on the market, thereby avoiding the necessity 25 of specially constructing a capping machine for a particular type of filler.

With the above general objects in view and others which will be obvious from the 30 following description, the invention consists in the features, details of construction and combinations of parts which will first be described in connection with the accompanying drawings illustrating one embodiment 35 of the invention and then more particularly pointed out.

In the drawings—

Figure 1 is a view in side elevation with parts in vertical section and parts broken away;

40 Figure 2 is a view in vertical section of the upper part of the apparatus shown in Fig. 1, showing the capping mechanism raised from capping position;

Figure 3 is a similar view showing the 45 parts lowered to capping position;

Figure 4 is a detail view showing in vertical section a portion of Fig. 2, the section being taken at right angles to the plane of Fig. 2;

50 Figure 5 is a sectional view taken on the line 5—5 of Fig. 2;

Figure 6 is a transverse sectional view (enlarged) taken through the apparatus shown in Fig. 1;

Figure 7 is a sectional view taken on the 55 broken line 7—7 of Fig. 6.

Referring to the drawings and more particularly to Fig. 1, the machine here illustrated as an example is supported by a base 100 having a standard 101 to which is secured a side frame 102 provided with bearings 103 for the drive shaft 104. This shaft is driven in any desired manner from a suitable

source of power, as, for example, by the belt 105 running on pulley 106, a suitable clutch 60 connection being indicated at 106^a. Secured to the drive shaft is a bevel gear 107 meshing with a similar gear 108 on a vertical shaft 109.

As hereinafter more fully described, the capping mechanism and the capping table 70 are driven from this vertical shaft 109. In order that the machine may be used to cap bottles of different sizes, i. e., quarts, pints

and the like, provision may be made for adjusting the relative stroke of the capping 75 head. In the present embodiment, the supporting table is relatively stationary and the capping mechanism is bodily movable with relation thereto. As shown, the capping

mechanism is carried by a head frame 110 80 supported on a column 111 which is slidable in the standard 101. To permit the sliding movement of the vertical shaft 109 when adjustment of the head is made, the gear 108

is provided with two keys 112 fitting in 85 corresponding key-ways in the shaft. Means is provided for raising and lowering the column in the standard. As here illustrated, the lower part of the column is provided

with a jaw 113 loosely embracing a nut 114 90 which is square in section and is threaded on a screw 115. Rotation and endwise movement of the nut is prevented by the jaw, as

appears in Fig. 1. The screw 115 carries a bevel gear 116 meshing with a similar gear 95 117 on a shaft 118 adapted to be rotated by a crank or handle (not shown). It will be

seen that when this shaft is turned, as the screw 115 cannot move endwise, it forces the nut 113 and with it the column 110 up- 100 wards or downwards, as the case may be.

When the parts are not being adjusted, the column is locked in the standard by clamping 120

wedges 119 and a clamping bolt 120.

There is provided a reciprocating capping 105 mechanism and a bottle supporting means,

bottles being delivered, one after another, to capping position beneath the capping

120

mechanism. As here shown as an example, the bottles are supported on a table 121 keyed to a vertical shaft 122 journaled in a bearing bracket 123. On this shaft is mounted a bevel gear 124 meshing with a similar gear 125 secured to a ratchet 126 provided with a plurality of spaced detents 127. The ratchet is driven by a pawl 128 pivoted to a wrist plate 129 and pressed against the ratchet by a spring-pressed plunger 130 carried by the wrist plate. Mounted on the shaft 109 is a bevel gear 131 meshing with a similar gear 132 on a horizontal shaft 133 on which is also mounted a spur gear 134 meshing with a similar gear 135 on a second horizontal shaft 136 which carries a pinion 137 meshing with a large gear 138 on a crank shaft 139. Mounted on the large gear 138 is an eccentric 140 fitting freely in a rocker arm 141 which rides upon it (Figs. 6 and 7). One end of the rocker arm (the upper end in Fig. 7) is pivoted to a link 142 which is in threaded relation with a rod 143 threaded into a bracket 144 which is pivoted on a pin 145 in the head 110. The opposite end of the rocker arm is pivoted to a link 146 which is in turn pivoted to the wrist plate 129. It will be seen that rotation of the crank shaft 139 oscillates the rocker arm, which in turn causes reciprocation of the wrist plate and the pawl, to drive the ratchet and the table. In order that the table may be held immovable between its periods of rotation, means is provided for automatically locking the ratchet and for automatically unlocking the same to permit movement. Although capable of various constructions, in that shown a lever 148 pivoted on a pin 149 carried by the head is pressed toward the ratchet by a rod 150 under the force of a spring 151. This lever 148 carries at one end a locking tooth 152 designed to enter the ratchet detents 127. As appears in Fig. 7 the tooth 152 is held by the spring-pressed plunger into one of the ratchet detents and consequently the ratchet and the capping table are locked against movement. For unlocking the ratchet, the locking lever has an extension 154 carrying a roller 155 adapted to be engaged by a tripper arm 156 carried by the wrist plate 157. This tripper arm is so designed that as the wrist plate completes its swing, the tripper engages the roller 155 and thus swings the lever 148 to cause withdrawal of the tooth 152, thus unlocking the ratchet. The wrist plate being moved by the stroke of the rocker arm 141 in a counter-clockwise direction from the position shown in Fig. 7, the pawl will slide idly over the ratchet wheel which is held locked, as above described. At or about the completion of this stroke, the tripper arm engages the roller 155 and the locking tooth 152 is withdrawn. At this point the pawl has en-

gaged the next ratchet detent. As the rocker arm makes its return stroke the pawl drives the unlocked ratchet forward, the locking tooth 152 sliding over the ratchet, until it drops into the next detent. At this point the pawl has completed its driving stroke and the ratchet is again locked, the parts being again in relation shown in Fig. 7 and ready for the next cycle. It will be seen, therefore, that for every revolution of the crank shaft 139, the capping table is given a period of movement and an equal period of rest. As the table rotates the bottles may be centered in proper position in any suitable manner.

The bottles thus being brought successively into capping position, are capped during the periods when the table is at rest. The capping mechanism here illustrated as an example includes a tubular plunger 58 sliding in bearing brackets 59 carried by the head frame. On its lower end this plunger has a throat carrier 60 which carries a bell-mouthed crown platform 61 and a throat ring or capping die 62. These elements may be of any suitable type known in the art and no further description is here necessary.

Within the tubular plunger 58 is a presser-foot or presser rod 63 which, as will appear from Figs. 2 and 3, is under the influence of a divided spring. The lower spring section 64 bears against skirted collars 65 and 66. The latter is engaged also by the middle spring section 67, the other end of which bears against a second skirted collar 68. This latter is also engaged by the upper spring section 69 which bears against a third collar 70. Collar 70 normally engages a shoulder 71 on the presser rod and a stiff recoil spring 72 bearing against the bottom of a yoke 73 threaded into the upper end of the plunger 58 and forming, in effect, a part thereof. At the bottom, the collar 65 engages a shoulder 74 on the presser rod, and normally (Fig. 2) against a ledge 75 formed in the plunger 58. This latter engagement thus acts as a stop to limit the relative downward movement of the presser rod.

As bottles nominally of a given size vary somewhat in height, the fixed relative stroke of the bottle support and the capping mechanism is predetermined to provide capping pressure for the shortest bottle of that size and provision is made for compensating for extra long bottles to avoid excess pressure being delivered to such bottles. Means is provided for operating the capping mechanism in such manner that the force operating thereon is rendered inoperative as soon as predetermined capping pressure is exceeded. This may be done, for example, by a structure including mechanism lowered with a fixed stroke and means

whereby its force is applied to the capping plunger only so long as the pressure between the capping mechanism and the bottle remains within the predetermined limit. In 5 structures embodying the invention to the best advantage, mechanism moved with a fixed stroke is provided having connection with the plunger and an outside element, movement of which is opposed by a predetermined force, the arrangement being such that the driven mechanism acts as lever on the plunger as long as the pressure between the capping mechanism and the bottle is less than said opposing force, 10 which is the chosen capping pressure, and thereafter as a lever on the outside element, allowing the plunger's movement to cease. This may take the form of a crank pin block sliding within mechanism acting as 15 a reversible lever, thus providing a slow down stroke and a quick return. Although capable of various constructions, in the present embodiment, on the crank shaft 139 is a crank disk 76 having a crank pin 77 20 set in a block 78 which rides in the track 79 formed in an oblong opening in a double ended toothed sector 80. Meshing with one end of this sector and secured to the plunger 58 is a rack 81. The diametrically opposite teeth of the sector mesh with an outside rack member 82 slidable in bearing brackets 83, 84 carried by the head frame. It will be seen that as the crank shaft revolves the block 78 reciprocates in the sector 25 80 and causes the latter to be raised and lowered and that this movement tends to raise and lower the two racks. Movement of the outside rack 82 is normally opposed by a predetermined pressure as 30 follows: Secured to its top is an extension in the form of a rod 85 carrying at its upper end a shouldered collar 86. Between the collar and the bearing bracket 83 is a coil spring 87 which tends to pull the rack 35 upwards. This upward movement of the rack is limited by a cupped washer 88 on the lower end of the rack engaging the lower bearing bracket 84. Thus the spring holds the rack to the limit of its upward 40 position and opposes any downward movement within the limits of its force. As the sector descends, therefore, the rack 82 is held against movement with a predetermined pressure, but the plunger 58 being 45 free to descend is lowered by the sector, that portion of the sector engaging the rack 82 merely riding over the same, so that the inter-meshing teeth act as successive fulcra, the sector thus becoming a lever for lowering the plunger. This condition continues 50 as long as the pressure between the plunger and bottle does not exceed predetermined capping pressure. Should an extra long bottle be encountered as soon as this predetermined pressure is exceeded, the force of 55

spring 87 is overcome. Thereafter, during the remainder of the downward stroke of the sector, its force is transferred to the rack 82, and the latter is lowered against its spring while the intermeshing teeth of 60 the sector with rack 81 act as successive fulcra. Thus, the lowering mechanism is rendered inoperative as regards the capping mechanism and the latter has no further movement. As the crank disc continues 65 its stroke and starts to move the sector upwards, the rack 82, provided, of course, that compensation has taken place, first returns to its normal position and thereafter the plunger is raised to its previous position ready for the next cycle. 70

In order that the foot of the presser rod may have the same relative position in the throat for successive operations, means is provided for determining its position by 75 limiting its relative upward motion. To this end, in the present embodiment, secured to the top of the presser rod, is a block 89 embraced within the yoke 73. This yoke (Fig. 2) terminates in a boss internally threaded to receive an adjustable stop pin 90 which is set at a given distance from the block. During the capping operation, the presser foot engages the bottle and thereafter remains stationary, thus having 80 in effect a relative upward movement which continues until the block 89 engages the pin 90, whereupon further relative movement is prevented and plunger and rod become as one. 85

In order to hold the bottle firmly in place during capping and to prevent it from being raised by the ascending throat after capping, means is provided for locking the presser rod in its capping position for a portion of 90 the capping cycle, and for releasing it again at the proper time to permit it to retake its normal position. Although capable of various constructions, in that here illustrated, bearing on opposite sides of the block 89, 95 are rollers 92 (Fig. 4) carried by a cage 93. These rollers are clamped between the block 89 and the inclined faces of a seat 94, by the upward movement of the cage caused by a spring 95, which bears against the cage and 100 a portion of the stationary frame. Thus, when the plunger 58 is raised subsequent to capping, the presser rod by the mechanism just described, remains locked down against the capped bottle and acts as a "knock-out" 105 to prevent the bottle from being lifted with the plunger. 110

This locking means is released at the proper time by mechanism which depresses the roller cage 93. In the present embodiment, straddling the yoke 73 and the block 89 and resting on the cage 93, is a depressing lever 96 pivoted to the frame at 97. Bearing on this lever is a nut 98 on a connecting rod 99 secured to the end of a bell-crank lever 120 125 130

165 pivoted on a pin 166. The opposite end of this bell-crank lever has a roller 167 riding on the periphery of the crank disc 76. This latter has a projection or lug 168 so positioned that it reaches roller 167 only after the ascending throat has cleared the capped bottle. The engagement of the lug with the roller swings the bell-crank lever 165 in a direction to pull down the connecting rod, thus 10 depressing lever 96. This depresses cage 93 releasing the locking action of the mechanism described and the presser rod is free to rise under the force of its spring, as hereinafter more fully described.

15 Means is provided for holding down lever 96 and for later releasing the same. As shown, lever 96 carries an abutment 170 engaged by a latch 171 on the end of a second bell-crank lever 172 also pivoted on pin 166 20 and carrying a roller 173 riding on the periphery of the crank disc. A spring 174 connecting the two bell-crank levers tends to hold the latch 171 against the abutment and both rollers against the disc. After the 25 lever 96 has been depressed it is held down by the latch until rotation of the crank disc brings the lug 168 into engagement with roller 173, which swings lever 172 to remove the latch from the abutment. This 30 releases the lever 96 and the cage returns to former position under the force of its spring, thus again locking the presser rod for the next cycle.

Since the presser rod, in case a bottle 35 should be missing, would be locked down so as to punch out the waiting crown, means is provided for releasing the locking means when the capping mechanism makes its full stroke unimpeded, i. e., when no capping 40 takes place. To this end, in the present construction, threaded onto the boss of the yoke 73 is a collar 175 so positioned that should the capping mechanism make its full stroke, it engages the lever 96 and depresses the 45 cage so as to release the presser rod on the upstroke. It is noted that as the capping mechanism makes this full stroke only when no bottle or no bottle tall enough to be capped is present, the collar 175 in no way 50 interferes with the normal operation elsewhere described.

In operation, the various parts being adjusted for the size of the bottles to be used, power is applied to the drive shaft and bottles are supplied to the capping table. 55 Through bevel gears 107, 108, shaft 109, bevel gears 131, 132, shaft 133, gears 134, 135, shaft 136, pinion 137, and large gears 138, shaft 139 is rotated. This shaft drives 60 the capping table through the eccentric 140, and the capping mechanism through the crank disc 76, and one cycle of operation is completed for each revolution of this shaft. Assuming that a bottle having been fed, as 65 before described, is in capping position, and

that the parts are in the position shown in Fig. 2, the crank disc rotating in a counter-clockwise direction, moves sector 80 downward and causes the capping plunger to descend, as before described. The bottle is further centered by the bell mouthed crown platform, and upon entering the latter, picks up the waiting crown. Almost immediately thereafter, the top of the crown engages the bottom of the presser rod, which thereafter 70 remains stationary, as the plunger continues to descend, the springs 64, 67, 69 yielding to permit this. During this operation collar 65 is separated from ledge 75 and the upward pressure of the three spring sections is transformed from the shoulder on the presser rod to the yoke through the stiff spring 71. This relative movement continues until the block 89 engages the stop pin 90 which determines the capping position of 75 the presser rod and thereafter the plunger and presser rod and are in effect one. The pressure of the presser rod and the capping throat or die on the cap, make a proper seal and crimp the cap skirt about the bottle in 80 the well known manner, compensation taking place as before described in case the bottle is over size.

Meanwhile the lug 168 on the crank disc has engaged the roller 173 to withdraw the 95 latch 171, thus freeing lever 96 and cage 93 to cause the presser rod to be locked in place. As the capping plunger starts to rise, the presser foot is held down tightly on the capped bottle, not only by the divided spring 100 but by the locking means referred to. Thus, the presser rod serves as a knock-out and the bottle is prevented from being lifted by the ascending throat. The three spring sections which were already under compression 105 between the shoulder 74 of the presser rod and the collar 70 are, by this relative upward movement of the plunger, further compressed between the ledge 75 in the plunger and the collar 70, which again bears against 110 shoulder 71. By the time the throat has cleared the bottle, the abutment 168 reaches roller 167 and swings bell-crank lever 165 to depress lever 96 and thus to force down cage 115 93 to release the presser rod, latch 171 holding the parts in this position. The presser rod, being released immediately returns to normal position under the force of the three spring sections, the stiff recoil spring 72 serving to bring the parts to rest without shock. 120

Meanwhile, during this cycle of the capping mechanism, the bottle supporting table drive has completed its cycle. While the capping operation is taking place, the table is locked at rest, the impelling pawl sliding 125 over the ratchet teeth on its idle stroke. As the rocker arm reverses, the pawl drives the table ahead one notch, this movement serving to cause the discharge of the capped bottle and to bring up the next bottle.

Thus, it will be seen each cycle moves a bottle to capping position, caps it and discharges its predecessor.

What is claimed is:

- 5 1. In packaging apparatus, and in combination, capping mechanism including a reciprocating capping plunger, a bottle support, an abutment, racks carried by said plunger and abutment, one of said racks being relatively movable with respect to its carrier, a driven element having a slot and having teeth meshing with said racks, a crank-pin-block mechanism working in said slot for bodily moving said driven element with a fixed stroke, and means for opposing relative movement of the relatively movable rack with a predetermined force, whereby the plunger is lowered toward the bottle support as long as predetermined pressure is not exceeded and is thereafter released. 70
- 10 2. In packaging apparatus, and in combination, capping mechanism comprising a capping plunger, a bottle support, a relatively movable abutment, means for opposing movement of said abutment with a predetermined force, a driven element having a slot, a crank-pin-block mechanism working in said slot for bodily moving said driven element with a fixed stroke, and connections 75 between said driven element and the plunger and abutment respectively whereby the driven element lowers the plunger toward the bottle support as long as a predetermined force is not exceeded, and thereafter moves 80 the abutment, the plunger being released. 85
- 15 3. In packaging apparatus, and in combination, capping mechanism including a capping plunger, a bottle support, a rack on said plunger, a relatively movable abutment having a rack thereon, a driven element having a slot and having teeth meshing with said racks, a crank-pin-block mechanism working in said slot for bodily moving said driven element with a fixed stroke, and means for opposing relative movement of 90 the abutment with a predetermined force. 95
- 20 4. In packaging apparatus, and in combination, capping mechanism comprising a reciprocable plunger, a reciprocable member, a continuously operated crank pin having a block secured thereto, mechanism in which said block slides, said mechanism having a connection with said plunger and said reciprocable member such that the descent of 100 said mechanism tends to cause the descent of both plunger and reciprocable member, and means for opposing descent of the reciprocable member within the limits of a predetermined force. 105
- 25 5. In packaging apparatus, and in combination, capping mechanism comprising a reciprocable plunger, a rack connected with said plunger, a second reciprocable rack, a toothed sector meshing with said racks, a trackway formed in said toothed sector, a crank pin, a block secured to said crank pin and sliding in said trackway, means for operating said crank pin, and a spring for opposing downward movement of said second rack. 110
- 30 6. In packaging apparatus, and in combination, a reciprocable capping plunger, a presser rod associated therewith and arranged to come into contact with the cap covered bottle during the capping operation, a clutch device arranged to lock the presser rod against relative upward movement with respect to the plunger, means, including a rotating member, for reciprocating the capping plunger, a cam device associated therewith, means operated by said cam device for unlocking said clutch device, and a latch device for holding the clutch device unlocked and arranged to be released by said cam device. 115
- 35 7. In packaging apparatus, and in combination, a reciprocating capping plunger, a presser rod associated therewith and arranged to come into contact with the cap covered bottle during the capping operation, a movable cage, rollers loosely mounted therein, a presser rod extension for engagement by said rollers, a member provided with inclined surfaces, a spring tending to move said cage to wedge the rollers between 120 said extension and the inclined surfaces, thereby to prevent relative upward movement of the presser rod with respect to the cage, means including a crank disk for reciprocating the plunger, a cam projection on 125 said crank disk, means operated by said cam projection for moving the cage against the spring to release the presser rod, and a latch also operated by said cam for holding said cage in releasing position. 130
- 40 8. In a capping apparatus, the combination with a capping plunger, of a rack secured to the plunger, a rack device, yielding means for holding said rack device in a normal position, a slotted gear element meshing with said racks, and a crank-pin-block mechanism working in the slot of said gear element for moving the latter bodily, whereby the plunger is actuated. 135
- 45 In testimony whereof, I have hereunto set my hand. 140
- 50 EDGAR P. DORMAN.
- 55 Witness:
SAMUEL W. TAYLOR.
